UNITED STATES PATENT OFFICE.

ARTHUR P. SPIRINGER, OF ERIE, PENNSYLVANIA.

DESIGN FOR A KIDDIE-CYCLE.

55,825.

Specification for Design.

Patented July 13, 1920.

Application filed March 19, 1919. Serial No. 283,678. Term of patent 14 years.

To all whom it may concern:

Be it known that I, ARTHUR P. SPIRINGER, a citizen of the United States, residing at Erie, in the county of Erie and State of Pennsylvania, have invented a new, original, and ornamental Design for Kiddie-Cycles, of which the following is a specification, reference being had to the accompanying drawing, forming part thereof.

In the drawings:

Figure 1 is a side elevation of the new design, and

Fig. 2 is a rear elevation of the same.

I claim:

The ornamental design for a kiddie cycle, substantially as shown.

ARTHUR P. SPIRINGER.
